[57] CLAIM

The ornamental design for an automobile audio speaker
enclosure, as shown and described.

DESCRIPTION

FIG. 1 is a front perspective view of an automobile
audio speaker enclosure showing my new design;

FIG. 2 is a rear perspective view;

FIG. 3 is a front elevational view;

FIG. 4 is a top plan view;

FIG. 5 is a bottom plan view;

FIG. 6 is a rear elevational view;

FIG. 7 is a right side elevational view;

FIG. 8 is a view like FIG. 1 of a second embodiment of
the speaker enclosure wherein the top and bottom front
flanges extend to the sides and the depth is reduced;

FIG. 9 is a view like FIG. 2 thereof;

FIG. 10 is a view like FIG. 3 thereof;

FIG. 11 is a view like FIG. 4 thereof;

FIG. 12 is a view like FIG. 5 thereof;

FIG. 13 is a view like FIG. 6 thereof; and

FIG. 14 is a view like FIG. 7 thereof.
